In Sweden July 21, 1937

14 Claims. (Cl. 123—192)

My invention relates to piston machines, such as combustion motors, provided with a crank-shaft, and more particularly to piston machines which impart to the surroundings vibrations which appear especially with motors having only 5 one or a few cylinders.

Such vibrations, for instance in combustion motors, depend to a great extent on the working conditions in the motor cylinders setting up 0 heavy continuously repeated changes of the turning moment in opposite directions due to alternating gas explosions and compressions. Hence, the crankshaft has a fly wheel which receives 5 the heavy impulses and delivers an even turning moment to the driven shaft. The stationary motor body is, however, nevertheless exposed to the oscillating reactive turning moments which are as great or even greater than those which the fly wheel has to take up. The impulses in 10 this reaction moment which are still more uneven than those which are taken up by the fly wheel are transferred directly through the motor body to the surroundings, which therefore are subjected to the said vibrations.

With combustion motors having a large number of cylinders, the turning moment and the corresponding reaction turning moment to the motor bed are equalized to a great extent if the machine is considered as a unit. Such large 0 motor plants with a long row of cylinders form, however, a yieldingly deformable member and the impulses due to the working conditions in the individual cylinders are therefore still imparted to the surroundings through the motor bed. In order to eliminate the unfavorable 5 influence of the reaction turning moment on operation of the motor, it has been suggested to provide rubber cushions or steel springs between a combustion motor and its support, whereby a damping is effected upon the transfer 0 of the reaction turning moments to the support. Even if the vibration phenomenon set up in the surroundings is in this way reduced to some 5 extent, it has not been possible with such simple means to eliminate the same, and the vibrations are still highly disturbing.

It is one object of my invention effectively to avoid disadvantages originating from the above-mentioned vibrations, and to provide a device which practically entirely relieves the bed supporting the motor, and hence the surroundings from the impulses of the reaction turning moments, so that the latter are converted to an even turning moment acting on the bed in the

same manner that the fly wheel equalizes the turning moment on the power output shaft of the machine. This is essentially accomplished by the fact that the turning pressure reaction impulses emanating from the piston mechanism on operation of the machine, are transferred through the machine body to the surroundings, for instance a base, by interposition of spring members, the machine body enclosing the piston mechanism being movably journaled about a 10 center common to the axis of rotation of the crank shaft of the machine while the machine body is dynamically or substantially dynamically balanced around this axis, so that the machine body with respect to the said pressure reaction 15 impulses oscillates as a pendulum with at least substantially unchanged center of gravity. The invention relates in the first place to machines being asymmetrical with respect to the axis of rotation of the crankshaft and for instance having vertical cylinder, whereby balance weights are provided which dynamically balance the 20 machine around its axis of rotation. The weight of the machine becomes by this decidedly greater, and the linear extension of the machine less 25 below that shaft.

In order to illustrate the inventive idea the following example will be assumed. A one-cylinder two-stroke motor develops 100 H. P. The number of revolutions of the motor is 30 300/min.=5/sec. The equalized turning moment of the motor is assumed to be delivered on a radial lever, the length of which is 0.5 m., reckoned from the crankshaft center of the motor. The power acting on this lever is then 5 kg./H. P., 35 or in all 500 kg. at about 15 m./sec. peripheral velocity. The motor has a fly wheel which is assumed to have a moment of inertia corresponding to a weight of two tons on the same radius of 0.5 m. As the motor works according to the 40 two-stroke cycle, its effect is delivered by the piston during a quarter of a revolution. The turning moment during this quarter accordingly becomes 2 tons on 0.5 m. radius. If further assuming that no power momentarily is delivered 45 from the motor shaft, the fly wheel takes up all the energy supplied and is thereby accelerated. The fly wheel which is equivalent to a weight of 50 2 tons is accelerated by a power of likewise 2 tons, and therefore its acceleration on the assumed inertia radius will be—the gravity, i. e. 9.8 m./sec., which is here approximated to 10 m. The acceleration takes place during a quarter of a revolution, in the assumed case corresponding to a time of 0.05 sec. The increase in velocity thus becomes 55

10.05=0.5 m./sec. Thereafter the fly wheel delivers the energy under a slower retardation to the shaft. The cylinder and the other parts of the motor body receive through the piston and the connecting rod, a reacting turning moment from the crankshaft which is as great as the turning moment which was transferred to the fly wheel. Assume now that the motor body has the same mass of 2 tons on 0.5 m. lever as the fly wheel. The mechanical condition will be the same as above described if, on the contrary, the fly wheel is imagined to be stationary while the motor body is allowed to rotate, with the mere difference that the fly wheel and the motor body have changed places.

A construction with rotating cylinder plant is often used on aero motors. The motor body will of course in this case be accelerated to the same degree as the fly wheel according to the aforesaid but in opposite direction, and the acceleration, on a radius of inertia of 0.5 m., during a quarter of a revolution is 0.5 m./sec. The power of acceleration is of course independent of whether the fly wheel or the motor body or both rotate, as both are subject to the same turning moment although in opposite directions. If, therefore, the fly wheel rotates with 5 revolutions/sec. and the motor body is made free so that it can rotate about the motor shaft, it will also now be subject to an acceleration of 0.5 m./sec. during a quarter of a revolution. As the time for a rotation of about a quarter of a revolution is 0.5 sec., the mean velocity and the distance performed=0.05·0.25=0.0125 m., or 12.5 mm. According to the invention a spring device is disposed between the motor body and its support, which device brings the motor body back towards the original position after each reaction impulse while delivering an even turning moment to the surroundings, whereby the motor body makes a pendulum movement with the crankshaft of the motor as the axis of rotation. Because of the fact that the motor additionally is balanced about this axis, vibrations originating from the turning reaction moments are effectively avoided.

The said spring device is preferably combined with means which automatically set the same, and thereby increase the spring power on increasing reaction turning moment and vice versa, so that the device can take up turning moments varying within broad limits without altering the position of the motor.

A further feature of the invention is to provide means for eliminating vibrations in the neighbourhood of the motor, originating from the unbalance of the reciprocating members (piston, connecting rod), of the motor. It is known to counterbalance said members by means which are heavier than the same, and which are adapted to move in paths equivalent to those of the members. In accordance with my invention the means comprise movable eccentric disc elements journalled on eccentricities on the crank-shaft, and balance weights journalled on said elements, whereby means are provided for guiding said weights.

Further and more detailed objects of the invention, together with the manner in which they and the above stated objects are attained, may best be understood from a consideration of the following description of the invention as embodied in suitable forms of machines, taken in conjunction with the accompanying drawings, forming a part of this specification, of which:

Fig. I shows a longitudinal section through a one-cylinder internal combustion motor constructed according to the invention.

Fig. II shows the motor viewed in the direction of the shaft, partly in section on the line II-II of Fig. I.

Fig. III shows a diagram illustrating the working manner of the motor.

Fig. IV illustrates diagrammatically the movable piston elements with their balance weights. 10

Fig. V shows a modified embodiment for balancing the inner movable piston members of the motor.

Fig. VI shows the same element partly in an axial section. 15

Figs. VII and VIII show side elevations of details pertaining to the same embodiment.

Fig. IX shows another embodiment of means for balancing the movable members of a machine, viewed in a vertical section in the plane of the 20 crankshaft on the line IX-IX of Fig. X.

Fig. X shows a section on the line X-X of Fig. IX.

Figs. XI and XII illustrate diagrammatically the machine according to this embodiment and a 25 detail thereof, respectively.

Fig. XIII shows a portion of a piston machine according to a further embodiment of the invention.

In the drawings, 10 designates the crank case 30 of the motor and 11 its cylinder in which works in known manner a piston 12. Piston 12 is connected by a connecting rod 13 to the crank pin 14 of a crankshaft 15, which latter carries a fly wheel 65. The crankshaft 15 is journalled in 35 bearings 16, which are rigidly fixed to the motor body 10. Motor body 10 is rotatably journalled in the base or frame 18 by the fact that the bearings 16 are provided with sliding surfaces against bearings 17 rigidly secured to the base. The 40 centers of these sliding surfaces are concentric with the axis of rotation 21 of the crankshaft. Below the shaft the crank case is formed as a balance weight 20 (Fig. II), which statically and 45 dynamically balances the motor body which is pivotable in the frame bearings 17 about the axis of the crankshaft. The weight of the motor aggregate becomes in this way greater below than above the crankshaft. The linear extension of the motor is nevertheless smaller in the lower 50 part. The motor is preferably symmetrical on each side of the symmetry plane II-II (Fig. I), in which all the forces on the piston, the connecting rod and the crankshaft are active.

The reaction turning moment on the motor on its operation is transferred to the stationary base 18 through a spring device, which in the embodiment according to Figs. I-IV consists in one or several springs 22, connected to a lever 23, rigidly secured on the crank case 10. Below the 60 spring 22 a piston 24 is arranged which moves in a cylinder 25 which, through a conduit 26, is in communication with another cylinder 27. The last-mentioned cylinder contains a servomotor slide valve 28 which, through a link 29, is movably attached to the lever 23. The valve 28 is provided with a side opening 31 and a cross channel 32 which in certain positions of the valve places the conduit 26 in communication either with a supply channel 33 for pressure oil, 70 or with an oil outlet 34. To the bottom of the servo-motor-cylinder 27 is connected an oil conduit 36 which is provided with a check valve 37. An oil discharge channel 38 extends from the cylinder 27 at a distance above its bottom. 75

Laterally of the elements 40 connecting the crank pin 14 with the crankshaft 15, and which in known manner may be round and concentric with the axis of the shaft, the crankshaft is provided with preferably forged eccentrics 41, the eccentricity of which is indicated by the center lines 42 and 21 in Fig. I. The stroke length of the eccentrics 41 is, in the embodiment according to Fig. I, about one third of the stroke length of the crank pin 14. Journalled on the eccentrics 41 are eccentric arms 43 which carry a member 44 provided with cylindrical outer sliding surfaces and which is guided by two vertical rods 45. On rotation of the crankshaft 15, the member 44 is given an up-and-down movement. The weight of the member 44 and the arm 43, is three times greater than the respective weight of the piston 12 and the connecting rod 13.

The cylinder 11 which may be water jacketed, preferably is connected through a conduit 50 to a silencer 51, as appears from Fig. I. The pipe 50 may be provided with spherical surfaces engagging flange 52 and a flange of the silencer 51. Packing rings 53 may be disposed in said surfaces. By this device the cylinder 11 may oscillate relatively to the stationary silencer 51, without jeopardizing the proper sealing at the gas exhaust.

The mode of operation is as follows:

The pulsating reactions acting on the motor body 10, 11, with its balance weight 20 are, during normal operation of the motor, transferred through the lever 23 and the spring member 22 to the stationary frame 18. The motor body 35 thereby acts as an oscillating fly wheel, while the spring 22 transfers an equalized reaction turning moment to the surroundings. The spring is automatically set against the lever 23 by the servo-motor cooperating with the spring, dependent on the size of the reaction impulses on the motor housing 10, 11. If the lever 23 is turned downwardly in Fig. II under the action of a heavy reaction impulse, the slide valve 28 will in a certain position open connection with the conduit 33 for pressure oil, which flows into the cylinder chamber 25 below the piston 24, resulting in a compression and setting of the spring 22. In a certain upper position of the slide valve 28 its channel 32 on the contrary, communicates with the discharge conduit 34, and oil can now flow out from the cylinder chamber below the piston 24. By this device the movability of the motor around the crankshaft is kept within a very limited range, at the same time as the turning moment is transferred to the motor bed by a sensitive spring with great setting length. This setting length or the piston stroke of the cylinder 25 is in accordance with the invention so determined that it is several 0 times, for instance ten times, greater than the oscillation amplitude of the motor body 10, 11. As stated above this oscillation amplitude may be kept within utmost reasonable limits and may thus on 0.5 m. radius be restricted to somewhat over one cm.

If the compression length of the spring is for instance ten times the swinging amplitude of the motor, the turning moment transferred to the surroundings varies with one tenth of the mean turning moment. If this mean turning moment is as in the above example one fourth of the maximum turning moment during the explosion period (in reality the difference is much greater), the reactive impulses transferred to the surroundings in a motor of conventional type will be de-

creased to one tenth of the mean turning moment, that is to 2.5% of the maximum value otherwise common. This means also that the shakings of the surroundings originating from the turning impulses of the motor, are decreased to a value which merely is some per cent of the common one.

From the diagram shown in Fig. III for the oscillation movements occurring during normal operation of the motor, it appears that rapid and heavy retardations and accelerations 55 and 56 respectively, are set up at the explosion during the crank stroke alternating with the relatively weaker returning forces 57 from the spring 22. The amplitude 58 gets the above mentioned size whereby, however, the continuous working condition differs from that described above, inasmuch as the motor body 10, 11, with its balance weight 20 during the explosion in the cylinder is first retarded to stationary position, and is thereafter accelerated in opposite direction. The time of 0.05 sec. above assumed is thus subdivided into halves, the one characterized by retardation and the other one by acceleration. These two periods of movement take place during a fourth of a whole stroke, while the remaining three fourths are characterized by a retardation and an acceleration, with a return force dependent on the setting of the spring 22. Assuming that this force is one fourth of the force set up in the cylinder during the explosion, this part of the swinging amplitude will be four times as long as the other one, and corresponds to the portion of the diagram positioned below the line 59 in Fig. III. The final result is thus in all events an amplitude which has a value of between one and two cm. in the above example.

Upon starting of the motor there is another condition acting than during normal operation, since the piston, when started from rest, is under the influence of the first explosion during a period several times longer than is the case when the motor works at full speed. This means that the fly wheel and the motor body are accelerated in opposite directions during the influence of an impulse of much longer duration than normal. The oscillation path or the amplitude would therefore, if allowed to be freely developed, increase to values which would be practically inconceivable. The slide valve 28 connected to the lever 23 is for this reason preferably formed as a dash pot or buffer piston which on large oscillating movement of the motor passes the outlet opening 38 of the cylinder 27, whereby oil confined in this cylinder below the opening 38 takes up the excess of turning moment of the motor.

In case the motor is to be constructed for reverse as well as for forward operation, driving a further spring device of similar kind may be provided on the opposite side of the motor shaft.

Fig. IV serves merely to illustrate the working manner of a device balancing the inner movable motor members. The piston is, as in the foregoing, designated by 12, and the connecting rod by 13. The counterweight 44 working between vertical guide members, is arranged diametrically opposite the piston 12, and cooperates with the same crankshaft as the piston by means of a connecting rod or lever 43, which in Fig. IV is half as long as the connecting rod 13. The stroke of the eccentric lever 43, is also half as long as that of the connecting rod 13. The counterweight 44 is in this case twice the weight of the piston 12 and, moreover, the weight of the arm 43 is twice that of the connecting rod 13.

The piston mechanism is obviously from dy- 75

namic point of view characterized by two reciprocating uniform movements, one of which has half the dimension of the other but works with double the weight. The balance is proper, as the center of gravity of the system always coincides with the axis of rotation.

In Figs. V-VIII an embodiment of a balance device for the piston mechanism according to the invention is shown, which permits a several times greater decrease of eccentricity or stroke length of the balancing masses. 12 again designates the piston, and 13 the connecting rod which, at one end, is journalled on the crank pin 14 of the crankshaft 15. For better understanding of this embodiment an imaginary eccentric arm 60 is illustrated in Fig. V, which at one end is journalled in the eccentric 61 diametrically opposite to the crank pin 14, and in its other end carries a balance weight 62. It is evident that the balancing elements 60, 61, 62, would operate in the manner aimed at according to the invention, even with such a small eccentricity in relation to the crank journal 14 as for instance 1:7, if they had a weight which were in inverse proportion as many times greater than that of the piston members 12, 13. This is accomplished according to the invention by the fact that the imagined eccentric 61 in reality corresponds to a larger eccentric 61a, but with the same center as the imagined one and moreover that the real eccentric 61a carries an "eccentric lever" or disc like member 60a, the outer circular circumference of which has the same center as the journal 68 of the eccentric lever 60, for the imagined counter-weight 62. The real eccentric disc 60a carries in the same manner as the imagined one the balance weight 62a, which surrounds the cylindrical outer surface of the eccentric disc 60a, and which is movable vertically between guides 63. The whole unit considered as a single mass or as a square disc, has obviously a common center of gravity which by movement from the eccentric 60a is made to move up and down under the geometrically determined acceleration conditions which are illustrated by the action of the imaginary eccentric rod 60 on the counter-weight 62. Also in this case the piston 12 gets an ideally proper counter-balance by the movement of the eccentric 61a, the eccentric disc 60a, and of the balance weight 62a. As appears from Fig. VI, the counter-weights on each side of the crank journal 14 may be provided with additional weights 64, for instance placed below the balance weights 62a.

The members balancing the piston mechanism produce vertical acceleration and retardation forces symmetric with the forces which act on the piston 12, and on the connecting rod 13, which latter however, may be said to correspond to a weightless imaginary eccentric lever 60. The movable counter-balancing members are therefore to be adapted also to balance those parts of the connecting rod, which more or less have an acceleration course characterized by the movements of the piston.

In the embodiment according to Figs. IX-XII, the same reference characters designate equivalent parts as in the foregoing embodiments. The crankshaft 15 is provided with two cylindrical eccentrics 123, the center lines 124 of which are eccentrically displaced relatively to the axis of rotation 21 of the crankshaft on the diametrically opposed side of the shaft 114. Around the cylindrical eccentrics 123 are provided two eccentric sleeves 125, which with their outer surface preferably being cylindrical are journalled in the

crank case 10, and the center lines 126 of which are positioned in a plane through the axis of rotation 21 of the crankshaft, and through the center line 127 of the piston pin 116 of the connecting rod 13. The eccentricity of the sleeves 125 is so chosen that the distance 128 (Fig. XII) between their axis 126 and the axis 129 of the eccentrics 123, is as many or substantially as many times smaller than the distance between the axis 114 and 127, as the distance between the axis 124 and 21 is smaller than the distance between the axis 114 and 21. In this way the motor case and the eccentric sleeves 125 move in the same manner as the element 12, 13, although on a decreased scale. The movement of the motor case and the sleeves 125, is diametrically opposed to the movement of the piston 12 and the connecting rod 13, respectively. The inventive idea may be illustrated in such way that a connecting rod 130 of the length 128 between its bearing centers, is imagined to be arranged between the axis of rotation 126 of the eccentric sleeves 125, and the axis of rotation 124 of the eccentrics 123 as indicated in Fig. XII. The bearing center 126 of this imagined diminutive connecting rod will on operation of the motor move vertically up and down in the same manner as the piston 12, although with a stroke length only corresponding to double the distance between the respective axes of rotation 21, 124, of the crankshaft 15 and the eccentrics 123. The other bearing center 124 of the imagined connecting rod 130, is moved in a circular path around the axis of rotation 21 of the crankshaft, corresponding to the rotational movement which is carried out by the crank 14 and its axis 114, respectively, around the same axis 21. From the aforesaid it is evident that the geometrical paths of the eccentric sleeves 125, which have the same function as the connecting rod 13, and of the motor case, are equivalent to the paths of the connecting rod 13 and the piston 12, merely with the difference that the first mentioned paths are diametrically opposed to the last mentioned, and moreover to a great extent decreased.

In the embodiment according to Figs. IX-XII, the crank 14 is provided with counter-weights 132, which balance the crank about the axis of rotation 21. The balance obtained by movably journalling the motor case 10, 11, is therefore equivalent to a straight-line up-and-down movement of the motor case. The motor case is in this embodiment guided by two bars 133 (Figs. IX and XI), the one end 134 of which is concentrically journalled about the rigid bearings 17, and the other end 135 of which is pivotally connected to the crank case 10. By these bars the vertical up-and-down movement of the motor case is arcuate. Thus the movement does not take place exactly along a straight line. However, as its amplitude is very small, the actual path of movement will differ merely by a few degrees from a straight line, which is without practical importance. The bars may of course be replaced by guides or the like, provided for instance on the rigid bearing housings 17, which give an exact straight-line movement.

If a piston machine, for instance of the one-cylinder type, is imagined to float freely in the air with its various members, such as piston, connecting rod, etc., working in normal manner, any reaction forces can obviously not be transferred to the foundation or surroundings due to the absence of contact with the same. As the machine is not influenced by outer forces, its center of

- gravity can therefore not be moved. If the piston for instance is moved up and down, the other parts of the machine will obviously move in a similar manner although in opposite direction.
- 5 Assuming that the weight of the piston for instance is 4% of the total weight of the other motor members, the amplitude of the movements of the machine and the piston will be in inverse proportion to the weight or mass of the bodies.
- 10 With an amplitude of the piston of 10 cm., for instance, the other parts of the machine aggregate will in the above example make an up-and-down movement with 4 mm. amplitude.
- In accordance with my invention means are provided ensuring an ideal balancing in accordance with the aforesaid, i. e. so that outwardly acting forces are not set up. The unbalances occurring in the motor, for instance by the movement of the piston, are balanced by the motor case proper, by the fact that it positively is brought to make a diminutive movement of the same kind and in a path fully determined. The relations between the movements of the inner elements and of the motor are so chosen, that they are in inverse proportion to the masses of the respective parts. The center of gravity of the machine as a unit always has a constant or substantially constant position which coincides with the axis of rotation of the power output shaft of the machine. In accordance with the invention, the motor does not shake the motor bed, but vibrates only itself at the same time as the advantage of a rigidly journaled crankshaft is ensured according to the invention.
- 25 The movable motor case may in the embodiment according to Figs. IX-XII be prevented from rotating relatively to the surroundings by means of a spring member 136 diagrammatically indicated in Fig. XI. The motor may of course be provided with means for taking up and equalizing the uneven turning moments, such as described in connection with Figs. I-III.

Fig. XIII shows an embodiment in which the balance weights 132 for the crank are omitted, so that the center of gravity of the crank is spaced from the axis of rotation 21 of the crankshaft. Also in this case a balancing by means of the motor casing may be accomplished in accordance with the invention. In Fig. XIII, 123 designates the eccentrics of the crankshaft 15, the axis of rotation 124 of which lies at a distance from the axis of rotation 21 in the same manner as above described, i. e. this distance is in relation to the distance between the axes 114 and 21, as is the distance between the axis 126 of the eccentric sleeves 125 and the axis 124 to the distance between the axis 114 and 127 according to Fig. IX. The axis 21 was in other words the axis of the crankshaft in the foregoing embodiment. The bars 133 are in Fig. XIII concentrically journaled relatively to the axis 21. The axis 21 is, however, in turn displaced relative to the axis 137 of the crankshaft 15, so that the distance between the axis 21 and 137 is in relation to the distance between the axis 114 of the crank and the axis 137, as the relation between the masses of the motor case and of the crank. The axis of rotation 21 of the bars 133 in the embodiment according to Fig. XIII, being eccentric to the axis of rotation 137 of the crankshaft 15, is positioned in a plane through the axis 137 and 114. The axis 21 is positioned on the side opposite the axis 137, relative to the axis 114 of the crank. As the bars 133 are eccentrically journaled, the center of gravity of

the motor rotates around the axis of rotation 137 of the crankshaft, and copies on a decreased scale the movement of the crank 114. A full balance is achieved, or in other words the center of gravity of the motor as a unit will maintain a constant position coinciding with the axis 137 of the crankshaft, in spite of the unbalance of the crank. The rotational movement of the center of gravity of the motor case is combined with its up-and-down reciprocating movement to an oval path. The amplitude of the combined movement in up-and-down direction is somewhat greater than at the embodiment according to Fig. IX-XII.

The invention is applicable to all kinds of single or multi-cylinder machines with vertical cylinders. Moreover, the invention may be applied to compressors and other kinds of piston machines having vibrations. Multi-cylinder machines are suitably provided with separate spring means for each cylinder, which are built independent of each other. The advantages gained by the invention are especially noticeable at slow-rotating, for instance one-cylinder machines, for driving vessels such as fishing boats, or the like. According to my invention a strong and simple machine may be utilized without being forced to take into account irritating shaking of the hull of the vessel. The pressure oil required for the operation of the servo-motor in the embodiment according to Fig. I, may be taken from the oil circulation system of the motor. The eccentric disc 60a according to Figs. V-VIII, may be provided with an external bearing surface against the weight 62a, only extending through part of the circumference, that is to say a portion (a segment) of the disc at the lower end thereof in Fig. V. may be cut away. The inner bore of the frame 62a is in such case provided with a sliding or bearing surface in the form of an arc 40 which does not enclose the whole disc 60a.

The excenter sleeves 125 in the embodiment according to Figs. IX-XII, may on the outer face be journaled in needle bearings. The invention does not exclude supporting the whole motor aggregate on a soft resilient base, for instance in order to avoid noise vibrations. In this case the bearing housings 17 or the base supporting the same, may be mounted on a resilient support. In Figs. IX-XIII two different positive movements are shown, which eliminate the shaking action of the movable motor members on the surroundings. These positive movements are caused directly by the crankshaft. A greater number of other movements is, however, conceivable, and moreover the movements may be caused in other manner, for instance by means of cam members which positively act on the motor case.

From the foregoing description it will be apparent that numerous changes and modifications may be made within the scope of the invention, which is to be considered as embracing all forms of apparatus falling within the scope of the appended claims.

I claim:

1. In a device of the class described, a body structure, a piston reciprocable within said body, a crankshaft, said body being turnable with respect to said crankshaft in a plane normal to the axis of rotation of said shaft, supporting structure for turnably supporting said body about said crankshaft, said body being substantially dynamically balanced about its turning axis, and means for resiliently resisting turning of said body with respect to said supporting structure,

said means providing increasing resistance upon increasing turning of said body from a normal position.

2. In a device of the class described, a body structure, a crankshaft rotatably mounted in said body, a piston connected to said crankshaft and reciprocable within said body, supporting structure, said body being turnably mounted with respect to said supporting structure about an axis concentric with the axis of rotation of said crankshaft, said body being substantially dynamically balanced about said axis, and means for resiliently resisting turning of said body with respect to said supporting structure, said means providing increasing resistance upon increasing turning of said body from a normal position.

3. In a device of the class described, a body structure including a cylinder, a piston reciprocable within said cylinder, a crankshaft rotatable with respect to said body, supporting structure for turnably supporting said body in a plane normal to the axis of rotation of said crankshaft, said body being substantially dynamically balanced about its turning axis, the weight of that portion of said body on the side of said crankshaft occupied by said cylinder being substantially less than the weight of the portion on the opposite side, and means for resiliently resisting turning of said body with respect to said supporting structure, said means providing increasing resistance upon increasing turning of said body from a normal position.

4. In a device of the class described, a body structure including a cylinder, a piston reciprocable within said cylinder, a crankshaft rotatable with respect to said body, supporting structure for turnably supporting said body in a plane normal to the axis of rotation of said crankshaft, said body being substantially dynamically balanced about its turning axis, resilient means for resisting turning of said body with respect to said supporting structure, and means for varying the resistance to turning offered by said resilient means, so as to increase the resistance the further said body turns from a normal position.

5. In a device of the class described, a body structure including a cylinder, a piston reciprocable within said cylinder, a crankshaft rotatable with respect to said body, supporting structure for turnably supporting said body in a plane normal to the axis of rotation of said crankshaft, said body being substantially dynamically balanced about its turning axis, resilient means for resisting turning of said body with respect to said supporting structure, and means responsive to increasing tendency of said body to turn for increasing the resistance to turning offered by said resilient means.

6. In a device of the class described, a body structure including a cylinder, a piston reciprocable within said cylinder, a crankshaft rotatable with respect to said body, supporting structure for turnably supporting said body in a plane normal to the axis of rotation of said crankshaft, said body being substantially dynamically balanced about its turning axis, a movable abutment, spring means disposed between said body and said abutment for limiting turning of the body with respect to said supporting structure, and means responsive to an increase in the turning amplitude of said body for moving said abutment in a direction to increase the resistance to turning offered by said spring means.

7. In a device of the class described, a body structure including a cylinder, a piston recip-

rocable within said cylinder, a crankshaft rotatable with respect to said body, supporting structure for turnably supporting said body in a plane normal to the axis of rotation of said crankshaft, said body being substantially dynamically balanced about its turning axis, a movable abutment, spring means disposed between said body and said abutment for limiting turning of the body with respect to said supporting structure, and means responsive to an increase in the turning amplitude of said body for moving said abutment a distance substantially greater than said increase in amplitude and in a direction to increase the resistance to turning offered by said spring means.

8. In a device of the class described, a body structure including a cylinder, a piston reciprocable within said cylinder, a crankshaft rotatable with respect to said body, supporting structure for turnably supporting said body in a plane normal to the axis of rotation of said crankshaft, said body being substantially dynamically balanced about its turning axis, a piston abutment, spring means between said body and abutment for limiting turning of the body with respect to said supporting structure, means for applying fluid pressure to said piston abutment, a valve for controlling said fluid pressure, and means for adjusting said valve in response to variations in the turning amplitude of said body so that an increase in said amplitude results in an increase in the fluid pressure.

9. In a device of the class described, a body structure including a cylinder, a piston reciprocable within said cylinder, a crankshaft rotatable with respect to said body, supporting structure for turnably supporting said body in a plane normal to the axis of rotation of said crankshaft, said body being substantially dynamically balanced about its turning axis, a piston abutment, spring means between said body and abutment for limiting turning of the body with respect to said supporting structure, means for applying fluid pressure to said piston abutment, a valve for controlling said fluid pressure, means for adjusting said valve in response to variations in the turning amplitude of said body so that an increase in said amplitude results in an increase in the fluid pressure, and liquid buffer means for positively limiting said amplitude.

10. In a device of the class described, a body structure including a cylinder, a piston reciprocable within said cylinder, a crankshaft rotatable with respect to said body, supporting structure for turnably supporting said body in a plane normal to the axis of rotation of said crankshaft, said body being substantially dynamically balanced about its turning axis, a piston abutment, spring means between said body and abutment for limiting turning of the body with respect to said supporting structure, means for applying fluid pressure to said piston abutment, a slide valve for controlling said fluid pressure, means connecting said valve to said body so that the valve is moved by turning of the body, the valve being arranged to increase the pressure upon an increase in the turning amplitude of the body, and means associated with said valve providing a liquid buffer for positively limiting movement of said valve and the turning amplitude of said body connected thereto.

11. In a device of the class described, a body structure including a cylinder, a piston reciprocable within said cylinder, a crankshaft rotatable with respect to said body, supporting

structure for turnably supporting said body in a plane normal to the axis of rotation of said crankshaft, an eccentric rotatable with said crankshaft, a member eccentrically journalled on said eccentric, and a balancing weight rotatably mounted on said member and reciprocably guided with respect to said body.

12. In a device of the class described, a supporting structure, a dynamically balanced crankshaft rotatably mounted therein, a body structure including a cylinder, an eccentric on said crankshaft, said body structure being rotatably mounted on said eccentric and substantially dynamically balanced about its turning axis on said eccentric, a piston connected to said crankshaft and reciprocable within said cylinder, and means for limiting turning of said body structure with respect to said supporting structure.

13. In a device of the class described, a rotatable crankshaft having an eccentrically located crank pin, a reciprocable piston, a connecting rod for connecting said piston to said pin, an eccentric on said shaft 180° out of phase with respect to said crank pin, a member eccentrically journalled on said eccentric, a balance weight journalled on said member, the radius of curvature of the journal between said member and said balance weight being greater than the radius of curvature between said member and said eccentric, and means for guiding the movement of said weight in a path parallel to the path of travel of said reciprocable piston.
